CLAIM

The ornamental design for a seat cover, as shown and described.

DESCRIPTION

FIG. 1 is a perspective view of the seat cover in a deployed position, showing a top, a front, and a right side of the seat cover.

FIG. 2 is a perspective view of the seat cover in the deployed position, showing a bottom, a rear, and a right side of the seat cover.

FIG. 3 is a front elevational view of the seat cover in the deployed position.

FIG. 4 is a right side elevational view of the seat cover in the deployed position in which the left side view is a mirror image of the right side elevational view shown.

FIG. 5 is a rear elevational view of the seat cover in the deployed position.

FIG. 6 is a top plan view of the seat cover in the deployed position; and,

FIG. 7 is a bottom plan view of the seat cover in the deployed position.

Some of the straps of the seat cover are shown with a symbolic break in their length. The appearance of any portion of the straps between the break lines forms no part of the claimed design.

1 Claim, 7 Drawing Sheets
